UNITED STATES PATENT OFFICE.

THOMAS SONNE, JR., OF MONTREAL, CANADA.

GAME.

SPECIFICATION forming part of Letters Patent No. 743,343, dated November 3, 1903.

Application filed December 19, 1902. Serial No. 135,932. (No model.)

To all whom it may concern:

Be it known that I, THOMAS SONNE, Jr., of the city of Montreal, Province of Quebec, Canada, have invented certain new and useful Improvements in Game Apparatus; and I do hereby declare that the following is a full, clear, and exact description of the same.

My invention relates particularly to table games; and it may be said, briefly, to consist in providing in combination a game board or table having an inclosing cushioned rail, preferably of peculiar formation, a series of pockets disposed at intervals around the table within the rail, a series of marks extending in a line between each of the pockets and that adjacent thereto, and a series of movable objects, preferably in the form of miniature yachts, adapted to be set upon the marks of said series one after the other or in irregular order, as may be desired, as the game is being played, while a billiard-ball and a cue or the like for striking same is provided, and one of said miniature yachts is utilized by each player.

For full comprehension, however, of the invention reference must be had to the accompanying drawings, forming a part of this specification, in which similar reference characters indicate the same parts, and wherein—

Figure 1 is a plan view of a game board or table constructed according to my invention. Fig. 2 is a transverse sectional view taken on line A B, Fig. 1; and Fig. 3 is a detail perspective view of one of the miniature yachts.

The game board or table according to the preferred embodiment of my invention consists of a bed *b*, covered, preferably, with billiard-cloth and having the playing-surface thereof inclosed by an octagonal cushioned rail, the alternate sides whereof are straight, as at *c*, and inwardly curved, as at *d*. Four pockets *e*, *f*, *g*, and *h*, preferably of cup shape, are formed, one adjacent to each straight side, and a series of sockets *i* are formed in lines extending between the pockets, while a pocket *j* is formed in the center of the table. The corner portions *k* of the table outside of the curved sides of the rail are provided with sockets *l*.

The movable objects preferably constitute miniature yachts, and each consists of a metallic or otherwise-weighted body portion *m*

of capstan form having an encircling cushion *a*, a downwardly-projecting peg *n* upon its under side, and a miniature mast *o* on its top, 55 with, preferably, a mainsail *p* and jib *q*.

The center pocket is preferably colored white and the others blue and red, alternately, and the sockets, which may be termed "buoys," are colored red, white, and blue, alternately, while the corner portions outside of the rail, which I term "anchoring-spaces," are colored red, white, yellow, and blue, respectively. A ball and a cue are provided for each player, and a game-board laid out 65 as above described will accommodate four players, in which case four balls *s* will be used, preferably colored red, white, yellow, and blue, respectively.

In playing the game the object is for the 70 players to advance their yachts over the course indicated by said sockets from and back to their starting-points, which are preferably the red and blue pockets, each player having previously selected a pocket. During play each player must cause his ball to drop into the pocket corresponding in color to the socket next in advance of that in which his yacht stands, or, if the game is being started, into the pocket corresponding in 80 color to the first socket to the right of the spot from which he plays. If an opponent's yacht is in the socket next in advance of that in which a player's yacht has stood at the time he scores, he places his yacht in advance 85 of his opponent. The play thus proceeds until one player completes the course, when he is adjudged the winner.

It is obvious that the pockets represent stake-boats and the sockets marking-buoys 90 indicating the race-course over which the yachts must pass. Of course these rules may be varied and the precise construction and arrangement of the parts changed, and, if desired, the game-board, without the stake- 95 marks and series of points between them, and with or without the miniature yachts or other like movable objects, may be used as a billiard-table or other scoring means than the pockets, balls, and cues used without departing from the spirit of my invention.

What I claim is as follows:

1. A game apparatus comprising a playing-surface having a series of stakes with distin-

guishing-marks, a series of points extending between said stakes and having distinguishing-marks corresponding to the marks upon said stakes, a movable object adapted to be moved from point to point of said series according to the score made by the player.

2. A game apparatus comprising a playing-surface having a series of stakes with distinguishing-marks, a series of sockets extending between said stakes and having distinguishing-marks corresponding to the marks upon said stakes, a movable object having a projection to fit into said sockets, said objects being adapted to be moved from socket to socket of said series according to the score made by the player.

3. A game apparatus comprising a playing-surface having a series of stakes with distinguishing-marks, a series of points extending between said stakes and having distinguishing-marks corresponding to the marks upon said stakes, a miniature yacht adapted to be moved from point to point of said series according to the score made by the player.

25 4. A game apparatus comprising a playing-surface having a series of stakes with distinguishing-marks, a series of points extending between said stakes and having distinguishing-marks corresponding to the marks upon said stakes, a miniature yacht adapted to be moved from point to point of said series according to the score made by the player, means for securing said yacht to said points.

5. A game apparatus comprising a playing-surface having a series of stakes with distinguishing-marks, a series of sockets extending between said stakes and having distinguishing-marks corresponding to the marks upon said stakes, a miniature yacht having a projection to fit into said socket, said objects being adapted to be moved from socket to socket of said series according to the score made by the player.

6. A game apparatus comprising a playing-surface having a series of pockets with distinguishing-marks, a series of points extending between said pockets and having distinguishing-marks corresponding to the marks of said pockets, a series of balls bearing distinguishing-marks, a series of miniature yachts bearing distinguishing-marks corresponding to the marks upon said balls, and means for detachably securing said yachts to said points, substantially as described and for the purpose set forth.

55 7. A game apparatus comprising a playing-surface having a series of pockets with distinguishing-marks, a series of sockets extending between said pockets and having distinguishing-marks corresponding to the marks of said pockets, a series of balls bearing distinguishing-marks, and a series of miniature yachts bearing distinguishing-marks corresponding to the marks upon said balls and 65 having downward projections adapted to fit

into said sockets, substantially as described and for the purpose set forth.

8. A game apparatus comprising a playing-surface having a series of pockets with distinguishing-marks, a cushioned rail inclosing 70 said playing-surface, a series of points extending between said pockets and having distinguishing-marks corresponding to the marks of said pockets, a series of balls bearing distinguishing-marks, a series of miniature 75 yachts bearing distinguishing-marks corresponding to the marks upon said balls, and means for detachably securing said yachts to said points, substantially as described and for the purpose set forth.

80 9. A game apparatus comprising a playing-surface having a series of pockets with distinguishing-marks, an eight-sided cushioned rail inclosing said playing-surface, a series of points extending between said pockets and 85 having distinguishing-marks corresponding to the marks of said pockets, a series of balls bearing distinguishing-marks, a series of miniature yachts bearing distinguishing-marks corresponding to the marks upon said balls, 90 and means for detachably securing said yachts to said points, substantially as described and for the purpose set forth.

10. A game apparatus comprising a playing-surface having a series of pockets with distinguishing-marks, an eight-sided cushioned rail inclosing said playing-surface and having its alternate side curved and straight, a series of points extending between said pockets and having distinguishing-marks corresponding 100 to the marks of said pockets, a series of balls bearing distinguishing-marks, a series of miniature yachts bearing distinguishing-marks corresponding to the marks upon said balls, and means for detachably securing said 105 yachts to said points, substantially as described and for the purpose set forth.

11. A game apparatus comprising a playing-surface having a series of five pockets with distinguishing-marks, an eight-sided cushioned rail inclosing said playing-surface and having its alternate sides curved and straight said pockets being disposed one in the center of the playing-surface and one adjacent to each straight side of the rail, a series of points 115 extending between said pockets and having distinguishing-marks corresponding to the marks of said pockets, a series of balls bearing distinguishing-marks, a series of miniature yachts bearing distinguishing-marks corresponding to the marks upon said balls, 120 and means for detachably securing said yachts to said points, substantially as described and for the purpose set forth.

In testimony whereof I have affixed my signature in presence of two witnesses.

THOMAS SONNE, JR.
